UNITED STATES PATENT OFFICE.

MARSHALL HENRY PEARSON, OF LEICESTER, ENGLAND, ASSIGNOR TO
UNITED SHOE MACHINERY COMPANY, OF PATERSON, NEW JERSEY.

EYELETING-MACHINE.

SPECIFICATION forming part of Letters Patent No. 683,488, dated October 1, 1901.

Application filed April 5, 1900. Serial No. 11,668. (No model.)

To all whom it may concern:

Be it known that I, MARSHALL HENRY PEARSON, a subject of the Queen of Great Britain, and a resident of No. 12 Victoria Park road, 5 5 Leicester, in the county of Leicester, England, have invented certain new and useful Improvements in Eyeletting-Machines; and I do hereby declare the following to be a full, clear, and exact description of the invention, such 10 as will enable others skilled in the art to which it appertains to make and use the same.

The present invention relates to machines for setting eyelets and lacing-hooks, and more particularly to that type of machine which is 15 designed to set the eyelets or hooks simultaneously in two layers of material, such as the sides of a shoe-upper.

The object of the present invention is to improve the construction and mode of operation 20 of a duplex eyeletting-machine, and particularly to render the punches and setting-dies more certain and uniform in their operation.

A further object is to improve the work-holding devices, whereby to positively insure 25 the immovability of the work during the operation of the punching and setting dies in forming the holes and setting the eyelets or hooks, and thus insure the correct and uniform action of such devices on the work.

A further object is to improve and simplify 30 the work-feeding mechanism and to provide simple means under the control of the operator for varying the feed of the work and also 35 to simplify the eyelet-feeding mechanism and to provide means whereby such mechanism may be thrown out of operation when the machine is employed in setting hooks instead of eyelets.

To the above ends and to secure other advantages obvious to one skilled in the art the present invention consists of the devices and combinations of devices which will be hereinafter described and claimed.

The present invention is illustrated in the accompanying drawings, in which—

Figure 1 shows a front elevation of a machine embodying the same with the lower part of the supporting-standard omitted. Fig. 50 2 shows a side elevation of the machine as it appears in Fig. 1 looking at the right. Fig.

3 shows a vertical section on the line xx , Fig. 2, with parts omitted, and also on the line yy , Fig. 2, through the clutch and driving-shaft. Fig. 4 shows a vertical sectional view 55 illustrating the construction of the punch-frame and the mode of operation of the punches and dies. Fig. 5 shows in an enlarged view the punch-frame removed, also showing the lower part of the guide-plate, together 60 with the edge-guide, the punch and setting-die in one side being shown in vertical section to illustrate the interior construction. Fig. 6 shows in front elevation and partial vertical section details of the mechanism, also 65 enlarged. Fig. 7 shows the cam-shaft removed from the machine and the cams and pulley thereon. Figs. 8, 9, and 10 show details of the start and stop mechanism. Figs. 70 11 and 12 show, respectively, a front elevation and a vertical sectional view of the hopper and attached chute. Figs. 13 and 14 are enlarged details hereinafter described. Fig. 15 illustrates separately from the rest of the machine the feed mechanism.

Similar reference characters will be employed to designate corresponding parts.

The machine comprises a frame or head 1, mounted upon a standard 2, (the upper part only of which is shown in the drawings.) In 80 the frame 1 are provided suitable bearings 3, in which is mounted the cam-shaft 4, which carries a series of cams $abcde$, and a pulley which actuates the several instrumentalities of the machine, as will hereinafter be described. Motion is imparted to the cam-shaft 4 by the pulley 5, which is constantly driven by a belt from any suitable source of power and which is coupled and uncoupled from the shaft 4 by the start and stop mechanism, 90 which will now be described.

Upon the shaft 4 is mounted a friction-disk 6, which is secured to said shaft so as to turn therewith and also to have a limited movement along said shaft by means of a key 7, 95 secured in the hub of the disk 6 and projected into an elongated keyway 8, formed in said shaft 4. The disk 6 has a beveled face 9, which when brought into contact with a leather or frictional surface 10, carried by 100 the pulley 5, will lock the disk 6 to said pulley 5 and cause the disk 6 and shaft 4 to par-

take of the rotary motion of the pulley 5, thus imparting motion to the movable parts of the machine. The disk 6 is moved along the shaft 4 to cause its beveled face 9 to engage the friction-surface 10 on the pulley 5 by means of springs 11, which are seated in a nut 12, threaded on the extended hub 13 of the disk 6, which springs bear against a collar 14, carried by a threaded bolt 15, screwed in the end of the shaft 4. The disk 6 on the opposite side of its periphery carries a beveled face 16, which is arranged to be brought into contact with a friction-surface 17, carried by a fixed annular brake-plate 18, which is provided with extended arms 19, (only one being shown,) which are adjustably secured, by means of threaded bolts 20 and threaded sleeves 21, to the integral arms 22 of the frame 1. It will be noted that the pulley 5 is recessed, as shown at 23, and that the disk 6 and annular brake-plate 18 are received in said recess and that the brake-plate may be adjusted with relation to the disk 6. The foregoing arrangement is such that a movement of the disk 6 by means of the springs 11 toward the pulley 5 will cause the pulley to turn said disk and the shaft 4 to set the machine in motion, and a movement of the disk 6 away from the pulley 5 and into contact with the fixed brake-plate will disconnect the pulley from the shaft and stop the machine, the pulley, however, continuing to rotate. It is designed that the movements of the disk 6 shall be produced by mechanism under the control of the operator, whereby he may cause the machine to make one or a series of cycles of operation, as desired.

Mounted to slide vertically upon a loose collar 24 upon the hub 13 of the disk 6 and confined between a flange 25 of said collar and an eccentric 26, formed in said hub, is a frame 27, which carries inclines 28, which co-operate with inclines 29, formed on the brake-plate 18, the arrangement being such that an upward movement of the frame 27 will permit the springs 11 to move the disk 6 into engagement with the pulley 5, and a downward movement of such frame will by means of the co-operating inclines 28 and 29 and the collar 24 and nut 12 move the disk 6 in the opposite direction to disconnect the disk 6 from the pulley 5 and connect it with the brake-plate 18, stopping the machine. The frame 27 is moved upwardly by means of a spring 30, which is seated in a recess 31 in the collar 24, and it is automatically moved downward by means of an eccentric-strap 32, which encircles the eccentric 26, formed in the hub of the disk 6, said eccentric-strap 32 reciprocating vertically during the rotation of the disk 6 and being guided by a pin 33, fixed to the depending arm 34 of the frame 27, which engages a slot 35, formed in a depending arm 36 of the eccentric-strap 32. Pivotally connected to the depending arm 34 of the frame 27 is a detent 37, which is provided with a notched dog 38, which when the de-

tent is rocked to the position shown in Fig. 9 is arranged to be engaged by a shoulder 39 on the arm 36 of the eccentric-strap 32, whereupon the downward movement of the eccentric-strap will cause the frame 27 to move downward to release the clutch and apply the brake, as before described. If the detent be rocked to the position shown in Fig. 8, the dog 38 will be disengaged from the shoulder 39 and permit the frame 27 to be raised by the spring 30 to release the brake and connect the clutch. The detent 37 is pivotally connected by a rod (not shown) to a foot-treadle, (not shown,) whereby it may be rocked as desired by the operator, it being clear that if it be held in the position shown in Fig. 8 the machine will continue to run; but as soon as the detent is rocked to the position shown in Fig. 9 the next downward movement of the eccentric-strap 32 will cause a downward movement of the frame 27 and the consequent stopping of the machine.

In the present machine, as heretofore stated, it is designed that the eyelets be set in both edges of the upper of a shoe simultaneously, the sides of the upper being laid together with the edges in alinement with or coincident with each other and placed in the machine with their inner surfaces lying against the opposite sides of a guide-plate and a die-plate and the edges of the upper in contact with a suitable edge-guide, which regulates the distance at which the eyelets are placed from the edges of the upper. While thus positioned the machine is set in operation, and the upper is gripped or clamped against the guide-plate by suitable clamping devices, the punches are operated to punch the holes, and the eyeletting-dies receive and insert the eyelets in the holes thus punched. Then the clamping devices release the upper, which is fed forward by the eyeletting-dies, all of which is accomplished in the machine of the drawings as follows:

The guide-plate 40 is secured to the frame 1 at the right hand thereof by means of screws 41, which pass through the shank of said plate, and said plate 40, as clearly shown in Figs. 1 and 6, extends angularly forward toward the right of the machine, whereby the upper may be accurately placed therein, said plate extending between the two flaps or sides of the upper, and the toe of the upper extending toward the left of the operator as he faces the machine. (See upper in dotted lines, Fig. 6.) Embracing the shank of the guide-plate 40 is an edge-guide 42, which has guide-faces 43 disposed upon opposite sides of the shank of the guide-plate and against which the edges of the upper bear and which is also provided with guiding flanges or wings 44, secured to the guide 42 by means of screws 441, which wings confine and guide the edges of the upper, preventing the lateral displacement thereof during the feeding movement. The edge-guide is provided with a hole which receives the pin 45, upwardly projected from

the guide-plate 40, and to which the edge-guide 42 is secured by means of the set-screw 451, the position of the edge-guide 42 on the said pin 45 determining the position of the 5 guide-faces 43 with relation to the point of operation of the punching and eyeleting devices.

The clamping devices in the machine of the drawings are shown at 46 and are carried 10 by or formed integrally with the arms 47 of the bell-crank levers 48, which are fulcrumed upon shafts 49, mounted in bearings 50 of the head or frame 1. The arms 47 extend downward and toward each other, as 15 clearly shown in Fig. 2, so as to bring the clamping devices 46 upon opposite sides of the guide-plate 40, against which the sides of the upper are clamped while being punched and the eyelets set. If desired, the clamping 20 devices 46 may have their inner faces provided with rubber or other soft surfaces 51 to prevent injury to the upper of the shoe. Each lever 48 has an arm 52, the meeting ends of which are provided with the interconnecting 25 head 53 and fork 54, whereby a rocking motion imparted to one of said levers will be imparted to the other to cause the clamping devices 46 to move toward and away from the guide-plate 40. This rocking movement in 30 one direction, preferably in the direction to bring the clamps 46 in contact with the work, is produced by a coiled spring 55, the opposite ends of which are secured, respectively, to the arms 47, and the rocking movement in 35 the opposite direction to release the work is produced by the cam *a*, the periphery of which is engaged by a cam-roll 56, carried by an arm 57, projected from one of the levers 48, as shown clearly in Fig. 2 of the drawings. The 40 cam *a* is preferably so formed as to permit the spring 55 to maintain the clamps 46 in contact with the work at all times except during the feeding of the work.

The punches and eyelet-setting dies in the 45 machine of the drawings are arranged as follows:

The punches 58 are threaded into tubular sleeves 59, which are mounted to slide in tubular bearings 60, so as to advance and retract the punches toward and from the work, 50 said sleeves being retained normally retracted, or in the position shown in Fig. 5, by means of springs 61, confined in the sleeves 59 and bearing at one end against the closed 55 end of the sleeves and at the opposite end against pins 62, fixed in the bearings 60 and passing through slots 63, formed in the sleeves 59. Each punch is provided with an ejecting-pin 64, arranged to slide therein and operate 60 to eject the piece of leather punched from the upper. The bearings 60 are supported by the yoke-shaped frame or support 65, which will be hereinafter called the "feed-frame," which is supported upon a shaft 66, mounted in bearings 67, carried by the arms 68 of a lifting-frame 69, which is fulcrumed on a shaft 70, mounted in bearings in the frame 1, and is

provided with an arm 71, carrying a cam-roll 72, which engages the cam-groove in the cam *b*, whereby the lifting-frame 69 is operated to 70 raise and lower the feed-frame for a purpose to be described. The feed-frame 65 also supports in bearings 73 below the bearings 60 the sliding tubular sleeves 74, into the inner end of which are threaded the setting-dies 75, 75 which may be of any usual or preferred form and provided with the sliding pins 76 for picking off and sustaining the eyelets. The tubular sleeves are maintained in the position shown in the drawings with the setting-dies 80 retracted and the pins 76 projecting therefrom by means of coiled springs 77, which bear at one end against a pin 78, fastened in the bearing 73 and passing through slots 78^x, formed in the sleeve 74 and also in a stop-sleeve 79, fitted in the sleeve 74. The outer 85 ends of the sleeves 74 are open, as at 80, and in the openings are fitted hardened blocks 81, which are backed up by strong springs 82, the inner ends of which bear against the end 90 of the stop-sleeve 79. The above arrangement is such that the two springs contained in the sleeves 74 act independently of each other, the springs 77 acting to return the sleeves to their retracted position and the 95 strong springs 82 permitting a cushioning or yielding actuation of the dies during the upsetting and the clenching of the eyelets.

Coöperating with the punches 58 and the setting-dies 75 is a die-plate 83, which is fastened to the feed-frame 65 by means of the headed bolt 84 and which has its lower end disposed between the two sets of punches and setting-dies and substantially in alinement with the guiding-plate 40, it being understood 100 that the lower end of plate 83 enters between the two sides or flaps of the shoe. The punches act against the smooth surface of the die-plate 83 in punching the holes for the eyelets, and immediately below the point where the 105 punches operate said plate 83 is provided on opposite sides with nipples or dies 85, which coöperate with the setting-dies 75 in upsetting and clenching the eyelets.

The punches and setting-dies are advanced 110 toward the die-plate 83 by means of bell-crank levers, hereinafter called "punch" and "die" levers 86, which are fulcrumed upon the same shafts 49 which support the work-clamp levers 48. The arms 87 of the punch and die 115 levers 86 are arranged to engage the sleeves 59 of the punches and also to engage the blocks 81 in the ends of the sleeves 74 of the setting-dies, as will be described, and the arms 88 of said levers are pivotally connected, as 120 by the pin-and-slot connection 89, so that motion imparted to one will be transmitted to the other and cause a simultaneous operation thereof. One of said punch and die levers is provided with a cam-roll 90, which 125 engages the peripheral cam *c*, whereby said levers are rocked to operate the punches and eyeleting-dies.

It will be noted that when the feed-frame

is in the position shown in Figs. 2 and 4 the ends of the punch-sleeves 59 are in position to be engaged and advanced toward the plate 83 by the punch-levers, and after the punches 5 have been actuated, the feed-frame is raised to place the sleeves of the eyeletting-dies in position to be engaged by the punch-levers, which will again be actuated to advance the setting-dies toward the die-plate 83 to cause 10 said dies to clench and set the eyelets. In this connection it should be stated that the cam *c* is so formed as to impart two oscillations to the punch-levers during a single cycle of motion of the machine, first to advance 15 the punches and then to advance the setting-dies, and that the cam *b* is so shaped and turned with relation to the cam *c* as to raise and lower the feed-frame alternately with the oscillations of the punch-levers. The 20 work is fed along by the setting-dies, and for this purpose while said dies are still in engagement with the eyelets which have been clenched or set the feed-frame is moved laterally with relation to the guide-plate 40 or 25 in the direction shown by the arrow in Fig. 6. This movement of the feed-frame 65 is accomplished by means of a link 91, one end of which is pivotally connected at 92 to the feed-frame 65 and the opposite end of which 30 is pivotally connected at 93 to a link 94, which in turn is pivotally connected to an arm 95, extending from a sleeve 96, said sleeve being mounted in bearings 98 in arms 99, projecting from the fixed frame 1. The sleeve 96 35 also has another arm 100, which engages a cam-path formed in the feed-cam *d*. (See Fig. 15.) The above arrangement is such that the rocking movement imparted to sleeve 96 by means of the cam *d* will be transmitted to the feed-frame 65, thus feeding the work along, as 40 hereinbefore described.

In order to adjust the feeding movement of the swinging feed-frame 65 to produce an 45 adjustment in the spacing of the eyelets, the following feed-adjusting mechanism is provided:

To the links 91 and 94 at the pivotal point 93 there is pivoted a link 102, which at its 50 lower end is pivoted at 103 to a feed-adjusting lever 104, carried by a rock-shaft 105, mounted in a bearing 106 of the fixed frame 1, and at its opposite end provided with an arm 107, to which is connected by a rod (not shown) 55 a foot-treadle, (not shown,) whereby the feed-adjusting lever may be rocked by the means described to change the position of the center of motion of the pivotal connection of the links 91 and 94, and thus regulate the throw 60 of the feed-frame 65. The swinging movement of the feed-adjusting lever 104 is limited by stops 108, which are arranged to be fitted into the openings in the quadrant-plate 109, which is mounted to have a slight swinging 65 movement, for a purpose which will hereinafter appear, upon the end of the shaft 105 in rear of the feed-adjusting lever 104. It will

be observed that while the amplitude of oscillation of the arm 95 is constant the amplitude of oscillation of the feed-frame 65 is variable and that the variations in amplitude of oscillation of the feed-frame are caused by changing the position of the pivot 103, whereby the horizontal component of the motion of pivot 93 is varied.

The eyelets are contained in a hopper 110, from which lead two eyelet-chutes 111, which are downwardly and forwardly extended and given a quarter-turn, so as to properly present the eyelets to the setting-dies, the lower 80 ends of the chutes being notched, as shown at 112, whereby when they are advanced into the line of movement of the setting-dies the pins 76 will enter and remove an eyelet from each chute. The chutes 111 are 85 preferably formed integrally with the bottom of the hopper 110, as shown, and said hopper is fulcrumed upon a shaft 113, fitted in bearing 114 of the frame 1, whereby the hopper and chutes may be rocked to advance 90 the chutes from the position shown in Fig. 1 to a position which will place their lower ends in line with the setting-dies. Said hopper is rocked in one direction, so as to advance the chutes to the point of operation of the setting-dies, by means of a spring 115, one end of 95 which is connected to an arm or lever 116, fixed to the shaft 113, and the opposite end of which is secured to the frame 1, said lever being provided with a cam-roll 117, which engages the cam *e* on the shaft 4, by means of which the hopper is rocked to retract the chutes. A rotating brush 118 is located within the hopper and is mounted on a shaft 119, which passes through a bearing 120 and carries at its outer end a pulley 121, driven by a belt 122, which passes over idle pulleys 123 and is driven by a pulley 124 on the driving-shaft 4. When the machine is used for punching holes for lacing-hooks, the chutes 111 are 110 prevented from moving, as described, and are held in their retracted position against the tension of the spring 115. This is accomplished by a spring-pressed pawl 118^x, carried by an arm 119^x, projected from the quadrant-plate 115 109 and arranged to engage the lower end of the lever 116, said quadrant-plate being rocked backward by means of the feed-adjusting plate 104 and the foot-treadle, as described, said feed-adjusting plate engaging the 120 stop 108 at the left, as shown in Fig. 13, and moving back the quadrant-plate to place the pawl in position to engage the end of the lever 116. The quadrant-plate is normally held from swinging to the left during the setting 125 of eyelets by means of stud 120^x, fitted to turn in a bearing in the standard 2 and passing through a circular opening 121^x, formed in the arm 119^x. The stud is cut away, as shown, the arrangement being such that when the stud is in the position shown in Fig. 3 the quadrant-plate may have a slight movement to the left, so that the hook 118^x may engage the lever 116 and prevent the hopper from 130

swinging; but when said stud is given a half-turn (to the position shown in Fig. 14) the said plate will be held from movement to the left.

5 The above-described arrangement is such that the distance between successive eyelets may be regulated within prescribed limits by the operator during the operation of the machine. In use the stop-pins 108 are set, so 10 that they determine the minimum and maximum distances, respectively, of the eyelets apart, the work being positioned in the machine and the stud 120^X being in the position shown in Fig. 14, whereby the quadrant-plate 15 is held from motion to the left by said stud and from motion to the right by the stud 122^X, mounted in the fixed frame of the machine. The machine is then set in motion and eyelets are set, the distances apart being regulated 20 by the operator through the treadle and rock-shaft 105, and when the requisite number has been set the operator rotates the stud 120^X to the position shown in Fig. 13 and depresses the treadle, which oscillates the 25 rock-shaft 105, so as to move the feed-adjusting lever 104 to the left, as shown in Fig. 3, so that it engages the left-hand stop-pin 108 and oscillates the quadrant-plate 109, so that the hook 118^X is brought into position to engage 30 the lever 116, (shown in dotted lines in Fig. 13,) which thus holds the eyelet-chutes 111 from moving forward, and the machine is operated to punch holes to receive the lacing-hooks which are inserted in another machine. It is thus seen that under these conditions 35 the movement for lengthening the distance between the holes simultaneously stops the supply of eyelets and causes the machine to operate simply as a punching-machine.

The operation of the machine of the drawings is as follows: The work is positioned in the machine as shown in dotted lines, Fig. 6, with both edges of the upper parallel to each 45 other and bearing against the edge-gage upon opposite sides of the guide-plate 40, the punch-plate 83, with the work-clamps 51, under the force exerted by the spring 55, clamping both edges of the upper, as described. 50 The detent 37 is now turned by the foot-treadle to permit the clutch to operate, imparting motion to the cam-shaft. The rotation of the cam-shaft causes the punch-levers to advance the punches toward the punch-plate 55 to punch holes in both edges of the upper. The punch-levers are then retracted and the feed-frame lifted by the lifting-frame to bring the setting-dies into the position formerly occupied by the punches and in line 60 with the holes formed by the punches, and so that the ends of the setting-die carriers may be engaged by the punch-levers. The punch-levers are then again operated to advance the setting-dies toward the complementary dies on the punch-plate, during which movement 65 the hopper and chutes are rocked and retracted, permitting the pins of the setting-

dies to remove an eyelet from each chute, which eyelets are carried toward the work and set or clenched in the holes formed by the punches. While the work is still held between the setting-dies and the punching-plate, the clamping devices are actuated to release the work and the feed-frame is rocked laterally to move the work forward, after 70 which the clamping devices again clamp the work and the feed-frame is returned and lowered for another operation of the machine. In this connection it is to be noted that the punch-levers are provided with laterally-projected offset ends 871, which hold the setting-dies against the work to hold and support the work during the feed movement of the feed-frame while the clamping-levers are released.

While I have shown in the drawings and described in this specification the preferred form of my invention, it is by no means specifically limited thereto, but is susceptible of embodiment in various forms without departure therefrom. Furthermore, it is to be understood that certain features of my invention are not limited to a duplex eyeleting-machine, but may be used in other forms of machines.

Having described the construction and mode of operation of my invention, I claim as new and desire to protect by Letters Patent of the United States—

1. In an eyeleting-machine, the combination with a pair of punches and a pair of setting-dies, of a support therefor, the members of each of said pairs being oppositely disposed, substantially as described.

2. In an eyeleting-machine, the combination with a guide-plate, of an edge-guide having a guiding-face upon opposite surfaces of said plate, substantially as described.

3. In an eyeleting-machine, the combination with a guide-plate, of work-clamping devices and means to actuate said devices to clamp the flaps of a shoe against opposite surfaces of said guide-plate, substantially as described.

4. In an eyeleting-machine, the combination with a pair of punches, of a support therefor, said pair of punches being oppositely disposed upon said support, and connected mechanism for simultaneously actuating both of said punches, substantially as described.

5. In an eyeleting-machine, the combination with a pair of oppositely-disposed punches, of a support therefor, means for actuating said punches, and means for moving said support with relation to the actuating means for the punches, substantially as described.

6. In an eyeleting-machine, the combination with a pair of oppositely-disposed punches, of a support therefor, means for actuating said punches, and means for moving said punches into and out of operative relation to the actuating means, substantially as described.

7. In an eyeleting-machine, the combination with a pair of oppositely-disposed punches and a pair of oppositely-disposed setting-dies,

- of a support therefor, means for independently and alternately actuating each member of said pair of punches and said pair of setting-dies, substantially as described.
5. In an eyeleting-machine, the combination with a pair of oppositely-disposed punches and a pair of oppositely-disposed setting-dies, of a support therefor, and a common actuating device for alternately and independently actuating each member of said pair of punches and said pair of setting-dies, substantially as described.
10. 9. In an eyeleting-machine, the combination with a support, of a pair of oppositely-disposed punches and a pair of oppositely-disposed setting-dies, supported in said support, a common actuating mechanism for said punches and setting-dies, and means to move the said support to place the punches and setting-dies alternately in position to be actuated by the common actuating mechanism, substantially as described.
15. 10. In an eyeleting-machine, the combination with a feed-frame, of a pair of punches and a pair of setting-dies disposed upon opposite sides of said frame, means for actuating said punches and dies and means for moving said dies while in engagement with the eyelets in the shoe for feeding the shoe, substantially as described.
20. 11. In an eyeleting-machine, the combination with a guide-plate, of clamping devices arranged to clamp a layer of work against the opposite surfaces of said plate, a pair of punches and a pair of setting-dies, and means to actuate said punches and setting-dies, substantially as described.
25. 12. In an eyeleting-machine, the combination with a guide-plate, of a pair of clamping devices co-operating with the opposite surfaces of said guide-plate to clamp the work, and means to move said clamping devices simultaneously toward and from the opposite surfaces of said guide-plate, substantially as described.
30. 13. In an eyeleting-machine, the combination with the setting-dies, and means to deliver eyelets thereto, of means for feeding the work, means under the control of the operator for adjusting the feed, and means actuated by the feed-adjusting mechanism for stopping the delivery of eyelets to the setting-dies, substantially as described.
35. 14. In an eyeleting-machine, the combination with two oppositely-disposed punches and two oppositely-disposed setting-dies, of supporting means therefor, means for actuating both punches simultaneously and both setting-dies simultaneously, means for holding the work, and means for moving the punches and setting-dies, first, to bring the setting-dies to the position just previously occupied by the punches, second, to feed the work, and third, to bring the punches back to their original position, substantially as described.
40. 15. In an eyeleting-machine, the combination with two oppositely-disposed setting-dies, of a feed-frame for supporting said setting-dies, means for actuating said setting-dies simultaneously, means for moving the feed-frame while the setting-dies are engaged with the work to feed the work, substantially as described.
45. 16. In an eyeleting-machine, the combination with a punch, a setting-die and a die-plate, of a common support therefor, of means for actuating the punch and setting-die, means for moving the support, first, to bring the setting-die to the position just previously occupied by the punch, second, to feed the work, and third, to bring the punch back to its original position, substantially as described.
50. 17. In an eyeleting-machine, the combination with a punch, a setting-die and a die-plate, of a common support therefor, means for actuating the punch and setting-die, means for moving the support, first, to bring the setting-die to the position just previously occupied by the punch, second, to feed the work while the setting-die is held against the die-plate by the means for actuating it, and third, to bring the punch back to its original position, and means for holding the work at all times except when the support partakes of its feed movement, substantially as described.
55. 18. In an eyeleting-machine, the combination with two oppositely-disposed punches, two oppositely-disposed setting-dies and a die-plate located between the punches and dies, of a common support therefor, means for moving the support, a guide-plate, and an edge-gage, substantially as described.
60. 19. An eyeleting-machine, comprising suitable mechanism, and means for causing said mechanism to simultaneously set two eyelets in axial alignment in two layers of work, one superimposed upon the other, and for causing said mechanism to feed the work while the eyelet-setting dies are in contact therewith, substantially as described.
65. 20. In an eyeleting-machine, the combination with a guide-plate, of an edge-guide having a guiding-face upon opposite sides of the plate, and guide-wings, substantially as described.
70. 21. In an eyeleting-machine, the combination with two oppositely-disposed setting-dies, of a common support therefor, means for actuating the setting-dies and means for moving the support to feed the work while both dies are in engagement with the work, and mechanism under the control of the operator for regulating the length of feed, substantially as described.
75. 22. An eyeleting-machine comprising suitable mechanism, means for causing said mechanism to simultaneously set two eyelets in axial alignment in two superimposed layers of work, means for causing said mechanism to feed the work while the setting-dies are in contact therewith, and means for holding the work at all times except when the work is being fed, substantially as described.

23. An eyeleting-machine comprising a die-plate, means for punching two holes in axial alinement in two layers of work separated by the die-plate, and means independent of the puncturing means for feeding the two layers of work on opposite sides of the die-plate, substantially as described.
24. An eyeleting-machine comprising two oppositely-disposed punches, two oppositely-disposed setting-dies and a die-plate located between the punches and setting-dies, respectively, substantially as described.
25. An eyeleting-machine, comprising punches, setting-dies and a die-plate located between the punches and setting-dies, respectively, of means for causing the punches and setting-dies to operate successively, the former to punch holes in two layers of work separated by the die-plate and the latter to set two eyelets in axial alinement in the two layers of the work also separated by the die-plate, substantially as described.
26. An eyeleting-machine having punching devices, two oppositely-acting setting-dies adapted to feed the work and a die-plate coacting with the setting-dies both to set the eyelets and to feed the work, substantially as described.
27. An eyeleting-machine having punching devices, two oppositely-acting setting-dies adapted to feed the work and a die-plate adapted to coact with both setting-dies, said die-plate being stationary with relation to the punching devices and setting-dies, substantially as described.
28. An eyeleting-machine having punching devices, two oppositely-acting setting-dies adapted to coöperate to feed the work, and means for holding the work at all times except during the feeding thereof, substantially as described.
29. An eyeleting-machine comprising setting devices for automatically and simultaneously setting two eyelets in two separate pieces of work, respectively, said setting devices being arranged to receive and resist the thrust of each other and to coöperate to feed the work, substantially as described.
30. An eyeleting-machine comprising two oppositely-disposed punches, two oppositely-disposed setting-dies, mechanism for actuating both of the punches and both of the setting-dies, the said machine having means for moving the punches and dies with relation to the actuating means therefor, substantially as described.
31. An eyeleting-machine comprising two oppositely-disposed punches, two oppositely-disposed setting-dies, and mechanism for actuating both the punches and the setting-dies, said machine having means to bring the actuating devices into coöperation with the punches and setting-dies alternately, substantially as described.
32. An eyeleting-machine comprising setting devices for simultaneously setting two eyelets in axial alinement, and for feeding the work while both dies are in engagement with the work, and means for varying the movement of said setting devices to regulate the feed, substantially as described.
33. An eyeleting-machine comprising an eyelet-setting die provided with a central spring-pressed eyelet-receiving pin, means including a spring for actuating the setting-die during its eyelet-setting motion, substantially as described.
34. An eyelet-setting device comprising a cylinder provided on one end with a riveting-face having a central hole therethrough, an eyelet-receiving pin supported in said hole, a light spring for holding the said eyelet-receiving pin outward, a plug in the end of said cylinder supported therein by a heavy spring, substantially as described.
35. In an eyeleting-machine, the combination with a guide-plate, the opposite sides of which guide the two sides of the top of a shoe, of a die-plate located adjacent to and in substantially the same plane as the guide-plate, substantially as described.
36. In an eyeleting-machine, the combination with two oppositely-disposed punches, and two oppositely-disposed setting-dies, of a die-plate interposed between the punches and setting-dies, respectively, means for supporting the punches, dies and die-plate, and means for actuating the punches and dies, substantially as described.
37. In an eyeleting-machine, the combination with two oppositely-disposed punches, and two oppositely-disposed setting-dies, of a die-plate interposed between the punches and setting-dies, respectively, means for supporting the punches, dies and die-plate, means for actuating the punches and dies, and means for holding the work, substantially as described.
38. In an eyeleting-machine, the combination with two oppositely-disposed punches and two oppositely-disposed setting-dies, of a die-plate interposed between the punches and setting-dies, respectively, means for supporting the punches, dies, and die-plate, means for actuating the punches and dies, means for holding the work, and means for moving the punches and setting-dies, first, to bring the setting-dies to the position just previously occupied by the punches, second, to feed the work, and, third, to bring the punches back to their original position, substantially as described.
39. In an eyeleting-machine, the combination with two oppositely-disposed punches, two oppositely-disposed setting-dies, a die-plate located between the two punches and the two dies, respectively, of a support for said parts which sustains them continuously in the same operative position with relation to each other, and means for moving the support, substantially as described.
40. In an eyeleting-machine, the combination with a pair of oppositely-disposed punches, a pair of oppositely-disposed setting-

dies located adjacent to the punches, and a die-plate located between the punches and between the setting-dies and coöperating with said punches and setting-dies, of a support 5 for said parts which sustains them continuously in the same operative position with relation to each other, means for actuating the punches and setting dies, means for moving the support, and means for holding the work, 10 substantially as described.

41. In an eyeleting-machine, the combination with a pair of oppositely and horizontally disposed punches, a pair of oppositely and horizontally disposed setting-dies, and a die-plate 15 interposed between the punches and dies, respectively, of a movable support for said punches, dies and die-plate, means for actuating the punches and dies, and means for moving the support to feed the work, 20 substantially as described.

42. In an eyeleting-machine, the combination with a pair of oppositely and horizontally disposed setting-dies and a die-plate therebe-

tween for setting the eyelets in the opposite sides of the top of a shoe, of a support for 25 said dies, means for actuating the dies to set the eyelets, and means for moving the support to feed the shoe, substantially as described.

43. In an eyeleting-machine, the combination with a pair of oppositely and horizontally disposed setting-dies and a die-plate therebetween for setting eyelets in the opposite sides of the top of a shoe and for feeding the shoe, 30 of a support for the dies and die-plate, means 35 for actuating the dies to set the eyelets, means for moving the support to feed the shoe, and means acting to hold the shoe at all times except during the feeding movement, substantially as described.

In testimony whereof I affix my signature in presence of two witnesses.

MARSHALL HENRY PEARSON.
